CLAIM

The ornamental design for a portable electronic device mount for a vehicle steering wheel, as shown and described.

DESCRIPTION

FIG. 1 is a perspective view of a portable electronic device mount for a vehicle steering wheel;

FIG. 2 is a front view of the portable electronic device mount;

FIG. 3 is a left side view of the portable electronic device mount;

FIG. 4 is a right side view of the portable electronic device mount;

FIG. 5 is a top view of the portable electronic device mount; and,

FIG. 6 is a bottom view of the portable electronic device mount.

Phantom lines, where utilized, are for illustrative purposes only and form no part of the claimed design.
